CONTROL SYSTEM

James P. Houck and Ralph A. Geiselman, Pittsburgh, Pa., assignors to Westinghouse Electric Corporation, East Pittsburgh, Pa., a corporation of Pennsylvania

Application April 21, 1945, Serial No. 589,664

13 Claims. (Cl. 314—75)

This invention relates to control systems and in particular to control systems utilized in conjunction with arc furnace regulators.

Heretofore, it has been common practice to supply arc furnaces through a power transformer disposed to be connected through a circuit breaker to a source of power supply. The operators of the arc furnaces are not always skilled in the operation of the switching equipment and numerous breaker failures have been encountered because of the improper operation of the breaker. For example, when a short circuit is encountered as by reason of one or more of the electrodes being in contact with the furnace charge, the operator often tries to reclose the circuit breaker before the short circuited electrode is raised to a position to clear the charge. If the breaker is repeatedly closed against the fault, flashover within the breaker housing is encountered and the breaker is damaged.

An object of this invention is to provide in a control system for arc furnaces for regulating the feeding of an electrode and to control the operation of a circuit breaker to prevent its reclosing for the duration of a fault.

Another object of this invention is to provide for controlling the operation of a circuit breaker in the supply circuit to an arc furnace to prevent the reclosing of the circuit breaker unless the furnace is free of short circuit faults.

A more specific object of this invention is to provide a system and apparatus for preventing the operation of a circuit breaker in the supply circuit to an arc furnace to prevent the reclosing of the circuit breaker unless the furnace is free of short circuit faults and to insure the raising of the electrode in the furnace to clear the fault.

Other objects of this invention will become apparent from the following description when taken in conjunction with the accompanying drawings, in which:

Figures 1A and 1B form a composite drawing illustrating diagrammatically the circuits and apparatus utilized in an embodiment of this invention;

Fig. 2 is a diagrammatic illustration of limit switches employed in conjunction with the circuits of Figs. 1A and 1B, and

Fig. 3 is a diagrammatic illustration of the circuits and apparatus embodying the teachings of this invention as applied to an arc furnace having a different regulating system than the embodiment of Figs. 1A and 1B.

Referring to Figs. 1A and 1B of the drawings, 55

an electric furnace 10 is illustrated, the furnace comprising a receptacle 12 containing a charge 14 and three movable electrodes 16, 18 and 20. The electrodes 16, 18 and 20 are connected by conductors 22, 24 and 26, respectively, to the secondary windings of a power transformer 28, the primary windings of which are disposed to be connected through the contact members 30, 32 and 34 of a circuit breaker 36 to a source of power supply (not shown). As illustrated flexible cables 38, 40 and 42 connected to electrodes 16, 18 and 20, respectively, are disposed to be wound on winding drums 44, 46 and 48, respectively, which are disposed to be operated by motors 50, 52 and 54, respectively.

The motors 50, 52 and 54 comprise armature members 56, 58 and 60, respectively, and field windings 62, 64 and 66, respectively, the field winding of each motor being connected to an energizing source represented by the positive and negative symbols. In order to supply energy to the armature windings 56, 58 and 60, the armature windings are connected across the armature windings 68, 70 and 72, respectively, of main generators 74, 76 and 78, respectively. The main generators 74, 76 and 78 are provided with field windings 80, 82 and 84, respectively, which are connected to be supplied with energy from armature windings 86, 88 and 90, respectively, of exciter generators 92, 94 and 96, respectively. Each of the main generators and its associated exciter generator is disposed to be driven by a motor in accordance with well known practice, the motors not being shown for simplicity of the drawings.

In the embodiment illustrated, each of the exciter generators 92, 94 and 96 is illustrated as having four field windings although other forms of the exciter generators or combination of main generator and exciter generator may be utilized as long as the exciter is provided with two opposed control field windings as will be described. The exciter generator 92 is provided with two opposed control field windings 98 and 100, a self-excited field winding 102 connected in shunt relation to the armature winding 86 and a differential field winding 104 connected to be energized in accordance with the output voltage of the main generator 74. Likewise, the exciter generator 94 is provided with two opposed control field windings 106 and 108, a self-excited field winding 110 and a differential field winding 112 and the exciter generator 96 is provided with two opposed control field windings 114 and 116, a self-excited winding 118 and a differential field winding 120.

The control field windings 98, 106 and 114 are shown connected across rectifiers 122, 124 and 126, respectively, to be supplied therefrom with a unidirectional current that is a measure of the alternating current flowing through phase conductors 22, 24 and 26, respectively, in a manner hereinafter described, whereas the control field windings 108, 108 and 116 are connected across rectifiers 128, 130 and 132, respectively, which are disposed to be connected to supply energy that is a measure of the drop in voltage across the arc of electrodes 16, 18 and 20, respectively.

In the system of Figs. 1A and 1B the connections to the rectifiers 122, 124 and 126 and to rectifiers 128, 130 and 132 are controlled in a predetermined manner by the operation of one or more switching apparatus such as the electromagnetic switching device 134, the master controller 136, the independent phase manual controllers 138, 140 and 142 and the circuit breaker 36.

As illustrated, the master controller 136 may be employed for so controlling the excitation of exciter generators 92, 94 and 96 as to effect a simultaneous change in the operation of the electrode motor as to simultaneously raise or lower the electrodes 16, 18 and 20, respectively, depending upon the direction in which the controller 136 is manually actuated. The master controller 136 is provided with segments 144—146, 148—150 and 152—154 disposed in the "off" position for connecting the control field windings of exciter generators 92, 94 and 96 respectively, to sources of energy, and segments 156—158—160, 162—164—166, and 168—170—172 disposed in the "raise" position associated with generators 92, 94 and 96, respectively, and segments 174—176—178, 180—182—184 and 186—188—190, respectively, disposed in the "lower" position. In addition to these segments, a segment 192 is also provided in the "off" position, the purpose of which will become apparent hereinafter.

The controllers 138, 140 and 142 are similar in construction. The controller 142 comprises a drum 194 disposed for predetermined rotational and slidable movement whereby segments 196—198 or segments 200—202—204 are selectively moved to "raise" or "lower" or to "off" or "automatic" positions. In the position shown, the controller 142 is in the "automatic" position with the segments of the drum out of alignment with the pairs of contact fingers which they will bridge in the "raise" or "lower" positions. In the "automatic" position, three contact members 206, 208 and 210 engage contact fingers whereby control of the energization of the control field windings 114 and 116 lies in the operation of the electromagnetic switching device 134, the circuit breaker 36 and the master controller 136.

With the handle 212 of the controller 142 in the "automatic" position, a finger 214 carried by the shaft 216 is positively held by opposed springs on one side of an arcuate stop plate 218 to maintain a spring member 220 compressed between the drum 194 and a stop 222. The arcuate stop plate 218 is provided with a notch 224 so positioned that when the handle 212 is manually moved to the "off" position, the finger 214 is moved to a position where it is in alignment with the notch 224 and passes therethrough to the other side of the arcuate stop member 218 and the force of the spring 220 effects a sliding movement of the drum 194 and segments thereon to a position where the segments can bridge associated pairs of contact fingers when the handle 212 is rotated to the

"raise" or "lower" positions. The segments 226, 228, 230, 232 and 234 of controller 140 and segments 236, 238, 240, 242 and 244 of controller 138 correspond to segments 196, 198, 200, 202 and 204, respectively, of controller 142, controller 140 also being provided with contact members 246, 248 and 250 and controller 138 with contact members 252, 254 and 256 corresponding to contact members 206, 208 and 210, respectively, of controller 142.

In order to control the operation of the circuit breaker 36, a relay system comprising the relays 258, 260 and 262 and the electromagnetic switching device 134 is utilized. The relay 258 is provided with a winding 264 grounded at one end as at 340 and connected across the secondary winding of a transformer 265 the primary winding of which is disposed to be connected through a switch 268 to a source of supply. When energized the contact member 270 of the relay 258 is disposed to connect the energizing winding 272 of the switching device 134 across a source of supply represented by the positive and negative symbols. The electromagnetic switching device 134 is provided with a contact member 274 disposed when a manually operated switch 276 is in a circuit closing position and the winding 272 is energized to establish a circuit extending from the positive terminal of a source of supply (not shown) through the switch 276, contact member 274 of the device 134, contact member 278 of relay 263 and the energizing winding 280 of relay 262 to the negative terminal of the source of electrical energy to actuate the contact member 282 of relay 262 to a circuit closing position. The contact member 282 thus establishes a circuit through the winding 284 of a circuit breaker 36 to effect the operation of the circuit breaker to cause the contact members 30, 32 and 34 of the breaker 36 to connect the power transformer 28 to the source of power supply.

The electromagnetic switching device 134 is provided with a number of corresponding contact members for controlling the circuits to the rectifiers supplying the opposed control field windings of the different exciter generators. Thus contact members 286, 288 and 290 are disposed to be in open circuit position when the winding 272 is deenergized to interrupt the circuit to rectifiers 128, 130 and 132, respectively. Contact members 292—294, 296—298, and 300—302 associated with rectifiers 122, 124 and 126, respectively, are also disposed to be in the open circuit position when the electromagnetic switching device 134 is deenergized whereas contact members 304—306, 308—310 and 312—314, respectively, are in circuit closing position with respect to their associated rectifiers 122, 124 and 126, respectively.

Again referring to the circuit breaker 36, the breaker is provided with contact members 316, 318, 320, 322 and 324 disposed in a circuit opening position and a contact member 326 disposed in a circuit closing position when the main contact members 30, 32 and 34 of the breaker 36 are in a circuit opening position.

The contact member 316 functions when the circuit breaker 36 is in a circuit closing position to connect one end of the energizing winding 328 of an electro-magnetic trip device 330 to a terminal of a source of electrical energy, the other end of winding 328 being disposed to be connected through a trip switch 332 to the other terminal of the source of electrical energy. As illustrated, the circuit breaker 36 carries a lug 334 disposed 75 to move upwardly as the circuit breaker closes to

slide beyond a latch 336 carried by the trip device 330 whereby the latch 336 engages the lug 334 to hold the breaker in a circuit closing position until the winding 328 is energized to release the latch and consequently the circuit breaker.

The contact member 318 carried by the breaker 36 is disposed to close an energizing circuit through the energizing winding of relay 260 when the switch 276 is in a circuit closing position and the circuit breaker 36 is actuated to its circuit closing position whereby contact member 278 is actuated to a circuit opening position to effect the deenergization of the winding 284 of the breaker 36, the contact member 338 of relay 260 establishing a holding circuit for relay 260 as long as the switch 276 is held in circuit closing position and the electro-magnetic switching device 134 is energized.

The contact member 326 of the breaker 36 is disposed in a circuit closing position when the breaker 36 is in an open circuit position to establish a circuit extending from one end of the winding 264 of relay 258 to conductor 24 whereby the winding 264 is effectively deenergized when a short circuit of any one of the electrodes 16, 18 and 20 in the furnace is encountered. This is apparent for if one end of winding 264 is grounded as at 339, the other end will be grounded through contact member 326, conductor 24, through the secondary windings of the transformer 28, conductor 22 or 26, electrode 16 or 18 and the grounded furnace or directly through conductor 24 and electrode 18 to the grounded furnace depending upon which of the electrodes is short circuited. Of course, if a short circuit condition does not exist in the furnace, the winding 264 will not be deenergized when the contact member 326 is in a circuit closing position unless the switch 268 is moved to a circuit opening position to deenergize the transformer 266.

In addition to the trip switch 332, the electromagnetic trip device 330 is disposed to be energized and operated by an overload condition in the furnace 10. For this purpose, an overload protective device 340 is provided, being connected through current transformers 342, 344 and 346 associated with conductors 22, 24 and 26, respectively, and having a contact member 348 disposed upon the occurrence of a predetermined overload condition such as the flow of a predetermined current in any one of the conductors 22, 24 and 26, to be actuated to a circuit closing position to establish an energizing circuit for the winding 328 to trip the circuit breaker 36.

With the circuit breaker 36, the electromagnetic switching device 134, the master controller 136 and the individual controllers 138, 140 and 142 as described, the rectifiers 122, 124 and 126 are disposed to be connected to be supplied from the current transformers 350, 352 and 354, respectively, associated with conductors 22, 24 and 26, respectively, whereas the rectifiers 128, 130 and 132 are disposed to be connected across the arcs of electrodes 16, 18 and 20, respectively.

With the circuit breaker 36 in an open circuit position, the electrodes can be lowered only if the electromagnetic switching device 134 is energized. The electrodes can then be individually lowered by operation of the associated controllers 138, 140, 142 or they can be simultaneously lowered by moving controller 136 to the "lower" position. On the other hand, if the electromagnetic switching device 134 is deenergized, the rectifiers 122, 124 and 126 are connected directly across a separate

source of electrical energy to cause the operation of the electrode motors to raise the electrodes.

In order to provide for limiting the amount of movement of the electrodes in the "raise" and "lower" directions, suitable limit switches may be disposed to be operated by the movement of the electrodes to interrupt the circuits to the rectifiers associated with the opposed control fields of the respective exciter generators or to interrupt the field circuit itself. As an example of the use of limit switches, reference may be had to Fig. 2 of the drawings wherein limit switches 356 and 358 are disposed to be operated by a projection 360 carried by electrode 20 to interrupt the circuits to field windings 114 and 116, respectively, depending upon the direction of movement of the electrode 20. Similar limit switches (not shown) are provided for electrodes 16 and 18, it being understood that such limit switches are employed in conjunction with the circuit of Figs. 1A and 1B but are not shown thereon in order to simplify the drawings.

In operation, with the circuits and apparatus as shown, the switch 268 is moved to a circuit closing position to supply power to transformer 266 whereby the winding 264 of the relay 258 is energized to actuate the contact member 270 to a circuit closing position. The contact member 270 establishes an energizing circuit for the winding 272 of electromagnetic switching device 134 whereby contact members 274, 286, 292, 294, 288, 296, 298, 290, 300 and 302 of the switching device 134 are actuated to circuit closing positions and the contact members 304, 306, 308, 310, 312 and 314 of the switching device 134 are actuated to circuit opening positions.

The movement of the contact member 274 of the switching device 134 sets up an energizing circuit for the winding 280 of relay 262 which may be established by the manual operation of the switch 276 to a circuit closing position. With the winding 280 of relay 262 thus energized, the contact member 282 of relay 262 is actuated to a circuit closing position to establish the energizing circuit for the winding 284 of circuit breaker 36, whereby the contact members 30, 32, 34, 316, 318, 320, 322 and 324 of the circuit breaker are actuated to circuit closing positions and the contact member 326 is actuated to a circuit opening position.

As the circuit breaker 36 moves to the circuit closing position for the contact members 30, 32 and 34, the lug 334 carried by the circuit breaker slides over the latch 336 of the trip device 330 and is engaged thereby to hold the circuit breaker 36 in circuit closing position until the winding 328 of the trip device 330 is energized to effect the tripping of the breaker.

The electrodes 16, 18 and 20 are lowered toward the charge 14 in the furnace 10 by moving the master controller 136 to the "lower" position where segments 174, 176, 178, 180, 182, 184, 186, 188 and 190 are in engaging relation with cooperating contact fingers whereby circuits are established from separate sources of electrical energy represented by the positive and negative symbols associated with each set of segments through rectifiers 128, 130 and 132 to effect the energization of the control field windings 100, 108 and 116, respectively. With control field windings 100, 108 and 116 energized in this manner the exciter generators 92, 94 and 96, respectively, are so excited as to control the excitation of the main generators 74, 76 and 78, respectively, to effect the operation of the electrode motors 50, 52 and 54,

respectively, to the lower of the electrodes 16, 18 and 20 respectively. These circuits may be traced from the positive symbol shown below each of the controllers 138, 140 and 142 through segments 178, 184 and 190 of the master controller 136 to a terminal of the rectifiers 128, 130 and 132, respectively, from the opposite terminal of the rectifiers through contact members 286, 288 and 290, respectively, of the electromagnetic switching device 134, segments 179, 182 and 188, respectively, of the master controller 136 to the negative terminals of the separate sources of supply.

The motors 50, 52 and 54 are thus operated to lower the electrodes 16, 18 and 20, respectively, until an arc is established, at which time the master controller 136 is returned to its "off" position and the opposed control field windings of the exciter generators 92, 94 and 96, respectively, assume the automatic regulation of the positioning of the electrodes 16, 18 and 20.

Under the conditions of automatic operation, the field windings 100, 108 and 116 are supplied by the rectifiers 128, 130 and 132, respectively, these rectifiers being connected by circuits which extend from conductors 22, 24 and 26, respectively, through contact members 324, 322 and 320, respectively, of the breaker 36, contact members 252, 246 and 206, respectively, of the controllers 138, 140 and 142, respectively, segments 144, 148 and 152, respectively, of the master controller 136, contact members 286, 288 and 290, respectively, of the electromagnetic device 134 through the rectifiers 128, 130 and 132, respectively, contact members 254, 248 and 208, respectively, of the individual controllers to the common segment 192 of master controller 136 and from thence to ground.

At the same time, the control field windings 98, 106 and 114 of the exciter generators 92, 94 and 96, respectively, are supplied from rectifiers 122, 124 and 126, respectively, which are connected in circuits extending from the current transformers 350, 352 and 354 through contact members 256, 250 and 210, respectively, of the controllers 138, 140 and 142, respectively, segments 146, 150 and 154, respectively, of the master controller 136, contact members 294, 298 and 302, respectively, of the electromagnetic switching device 134, through the rectifiers 122, 124 and 126, respectively, contact members 292, 296 and 300, respectively, of the switching device 134, contact members 254, 248 and 208, respectively, of the controllers 138, 140 and 142, respectively, to the common segment 192 of the master controller 136 and from thence to ground, whereby the field windings 98, 106 and 114 are energized in accordance with a measure of the current flowing in the conductors 22, 24 and 26, respectively.

With the electrodes 16, 18 and 20 properly positioned in the furnace 10, the arc potential and arc currents are properly balanced so that the opposed control field windings 98—100, 106—108 and 114—116 are in balance and the motors 50, 52 and 54, respectively, are not operated. Any tendency toward unbalanced relation between the arc current and arc potential immediately causes a change in the excitation of the exciter generators to effect immediate operation of the electrode motors to position the electrodes associated therewith so as to maintain an arc having a predetermined arc potential and arc current.

If, during the operation of the arc furnace, one or more of the electrodes should become short circuited as by reason of a cave-in of the charge 14 against one or more of the electrodes, the increase in current flowing through the conductor

22, 24 or 26 supplying the electrode thus short circuited effects operation of the protective device 340 to actuate the contact member 348 to a circuit closing position to effect the energization of the winding 328 of the trip device 330 to release the circuit breaker 36 and interrupt the supply of power to the power transformer 38. The movement of the circuit breaker 36 to the open circuit position for interrupting the power supply causes the contact member 326 to move to a circuit closing position to close a circuit from the ungrounded end of winding 264 of the relay 258 through the contact member 326 to conductor 24 and from thence to ground through the short circuited electrode and the grounded receptacle 12.

The closing of the ground circuit by the contact member 326 effectively shunts the winding 264 of relay 258 whereby the winding is deenergized and the contact member 270 moves to a circuit opening position to effect the deenergization of the winding 272 of the electromagnetic switching device 134. With the switching device 134 thus deenergized, contact members 274, 286, 292, 294, 298, 296, 298, 300 and 302 move to a circuit opening position and contact members 304, 306, 308, 310, 312 and 314 of the switching device 134 move to a circuit closing position whereby the rectifiers 122, 124 and 126 are supplied from a separate source of electrical energy. The circuits supplying the rectifiers 122, 124 and 126 under such conditions may be traced from the positive terminals of the separate sources of supply indicated adjacent the individual controllers through contact members 306, 310 and 314, respectively, of the switching device 134, rectifiers 122, 124 and 126, respectively, contact members 304, 308 and 312, respectively, of the switching device 134 to the negative terminals of the separate source of supply. With the rectifiers supplied in this manner, the control field windings 98, 106 and 114 of the exciter generators 92, 94 and 96, respectively, are so energized that the output of the exciter generators effects the excitation of the main generators 74, 76 and 78, respectively, to cause an operation of the motors 50, 52 and 54, respectively, to raise the electrodes 16, 18 and 20, respectively.

As shown in Fig. 2 of the drawings, unless some other condition changes the operation of the motors 50, 52 and 54 the limit switches are operated before the movement of the electrodes causes damage to the furnace and system. For example the lug 360 carried by the electrode 20 engages the trip switch 356 to interrupt the circuit to the field winding 114 to prevent operation of the motor 54 so as to prevent the raising of the electrode 20 beyond a predetermined limit. Although not shown, similar limit switches are provided to control the positioning of the electrodes 16 and 18.

It is to be noted that as the contact members 324, 322 and 320 of the circuit breaker 36 and contact members 286, 288 and 290, respectively, of the switching device 134 are in open circuit position they prevent energization of the field windings 100, 108 and 116, respectively, when a short circuit condition for the electrodes 16, 18 and 20, respectively, is encountered.

As soon as the short circuit condition clears, even though the circuit breaker is in its circuit opening position where the contact member 326 connects the ungrounded end of the winding 264 of relay 258 to conductor 24, the winding 264 is again energized to cause the contact member

270 to establish the energizing circuit for the winding 272 of the electromagnet switching device 134. Under such conditions, the contact members 324, 322 and 320 of the circuit breaker 36 being in an open circuit position prevents the energization of the field windings 100, 108 and 116 by any flow of current from the transformer 266 through the contact member 326. Thus until the circuit breaker 36 is again operated to its circuit closing position by the closing of the manual switch 276, the field windings 100, 108 and 116 remain deenergized to prevent lowering of the electrodes.

If during the automatic operation of the arc furnace it is desired to raise or lower any one of the individual electrodes 16, 18 and 20, the same may be accomplished by operating the associated individual controller 138, 140 and 142, respectively. For example, if it is desired to raise electrode 20, while maintaining automatic operation or control of the positioning of the electrodes 16 or 18, the handle 212 of individual controller 142 is moved from the "automatic" position to the "off" position where the finger 214 passes through the notch 224 in the arcuate stop member 218 and the drum 194 slides under the influence of the spring 220 to a position where the segments carried by the drum 194 are in alignment with the cooperating contact fingers. The handle 212 is then turned to the "raise" position where the segments 200, 202 and 204 engage cooperating contact fingers. In this position the segment 200 establishes a circuit from the current transformer 354 through the segment 200 directly to ground, thereby preventing an open circuit from the normal supply for the rectifier 126. At the same time the segments 202 and 204 cooperate to establish a circuit extending from the positive terminal of the separate source of supply through segment 204 of controller 142, contact member 302 of the switching device 134, rectifier 126, contact member 300 of the switching device 134, segment 202 of the controller 142 to the negative terminal of the separate source of supply.

If instead of raising the electrode it is desired to lower the electrode 20, the handle 212 is turned to the "lower" position where the segments 196 and 198 engage cooperating pairs of contact fingers to establish a circuit extending from the positive terminal of the separate source of supply through the segment 198, rectifier 132, contact member 290 of the switching device 134, segment 196 of the controller 142 to the negative terminal of the separate source of supply to effect the energization of the field winding 116 to cause an operation of the motor 154 to effect the lowering of the electrode 20. The operation of the controller 142 can be duplicated for either controller 138 or 140 where it is desired to effect independent positioning of the electrodes 16 and 18, respectively.

In another embodiment of this invention illustrated in Fig. 3 of the drawings, the same numerals are employed to identify like parts identified hereinbefore in the description of the circuits and apparatus of Figs. 1A, 1B and 2. As will be evident, the circuits and apparatus of these figures are similar with the exception of the regulator used in conjunction with each electrode, the circuit breaker 36, electromagnetic switching device 134, master controller 136 and individual controllers 138, 140 and 142 being modified somewhat in accordance with the changes in the regulator and circuits required therefor.

In the embodiment of Fig. 3, the electrode mo-

tor 54 is a reversible motor having an armature winding 60 and a separately excited field winding 68. In order to control the direction of operation of the motor 54, a pair of contactors 362 and 364 are employed for so changing the flow of current in the motor armature as to cause it to operate in the "raise" and "lower" directions respectively. The contactors 362 and 364 are provided with contact members 366 and 368, respectively, disposed for movement to predetermined circuit making positions depending upon the energization of the contactor windings 370 and 372, respectively.

As illustrated, one end of the contactor winding 370 is disposed to be connected through a limit switch 356 to a terminal represented by the negative symbol of a separate source of supply and one end of the contactor winding 364 is disposed to be connected through a limit switch 358 to the same terminal, the other ends of windings 370 and 372 being disposed to be selectively connected through contact member 374 of a balanced beam regulator 376 to the other terminal, represented by the positive symbol, of the separate source of supply when the controllers 136 and 142 are in the position shown.

The regulator 376 is of a type well known having two energizing windings 378 and 380 connected to be responsive to the arc potential and the current flowing through the electrode 20, respectively, so that when the windings are energized and the magnetic pulls are balanced the contact member 374 is in an intermediate position as shown. Each of the motors and regulators therefore represented by the blocks 382 and 384 for electrodes 16 and 18, respectively, are the same as the apparatus enclosed in the block 386 for the electrodes 20 and therefore need not be further described.

The controllers 138, 140 and 142 are similar having segments 388, 390 and 392 in the "lower," "off" and "raise" positions, respectively, whereas the master controller 136 has three sets of corresponding segments composed of segments 394, 396 and 398 in the "lower," "off" and "raise" positions, respectively, each set being associated with the regulating apparatus for one of the electrodes.

In this embodiment, the electromagnetic switching device 134 is similar to that in the embodiment shown and described with respect to Figs. 1A and 1B in that it has contact member 214 disposed for setting up the energizing circuit for the relay 262 and consequently for the circuit breaker 36. However, in this embodiment, the electromagnetic switching device has three sets of pairs of contact members 400 and 402 for cooperating in establishing predetermined circuits in conjunction with the master controller 136 and the independent controllers 138, 140 and 142. Since the regulators employed for controlling the operation of the electrode motors in this embodiment are different from those illustrated in Figs. 1A and 1B, the circuit breaker 36 utilized in this embodiment is devoid of the contact members 320, 322 and 324 utilized in the previous embodiment.

The operation of the embodiment of the invention illustrated in Fig. 3 is somewhat similar to that of the embodiment of the invention shown in Figs. 1A and 1B in that the closing of the switch 268 establishes the energizing circuit for the relay 258, the contact member 270 of which establishes the energizing circuit for the winding 272 of the electromagnetic switching device 134. When thus energized, contact members 274 and 400 of the switching device 134 are actuated to circuit closing positions and the contact mem-

bers 402 of the switching device 134 are actuated to circuit opening positions. The movement of the contact member 274 sets up the circuit which may be closed by manual operation of the switch 276 and extends through the contact member 278 of relay 260 and the energizing winding 280 of relay 262 whereby the contact member 282 closes the energizing circuit for the winding 284 of the circuit breaker 36. When thus energized, the circuit breaker 36 moves to a circuit closing position where its contact members 30, 32, 34 and 318 are in the circuit closing position and the contact member 326 is in a circuit opening position. As in the previous embodiment, when the circuit breaker 36 is thus actuated to close the circuit for supplying power to the power transformer 23, the latch 336 of the latching device 330 engages the lug 334 to maintain the circuit breaker in its circuit closing position until the winding 328 of the latching device is energized in a predetermined manner.

With power supplied to the power transformer 23 in the manner described, the electrodes 16, 18 and 20 may be lowered to engage the charge 14 in the furnace 10 and to establish an arc by a movement of the master controller 136 to the "lower" position where segment 394 engages co-operating contact fingers and a circuit for each of the regulators, described hereinafter with respect to only regulator 376, is closed extending from the positive terminal of a separate source of supply through contact member 400 of the switching device 134, segment 394 of the master controller 136, winding 372 of the contactor 364, limit switch 358 to the negative terminal of the constant source of supply. By establishing this circuit the winding 372 is so energized that the contact member 368 of the contactor 364 is actuated upwardly to a circuit closing position. The circuit thus established extends from the positive terminal of a separate source of supply through the contact member 368, armature member 60 of the motor 54 and contact member 366 of the contactor 362 to the negative terminal of the separate source of supply, whereby the motor 54 is operated to effect a lowering of the electrode 20. Simultaneous positioning of the electrodes 16 and 18 is obtained by the operation of the motors and regulators in the blocks 382 and 384 through the circuits established by the associated segments 394 of the master controller 136. As soon as the arc is established, the master controller 136 is returned to its neutral position, whereby automatic operation of the electrode motor associated with each electrode is obtained in response to variations in the arc potential and arc current.

For example, if the arc current should increase, the current flowing through the current transformer 354 so energizes the winding 380 of the regulator 376 as to overcome the balance or pull of the winding 378 and cause the contact member 374 to move to a circuit closing position. The movement of contact member 374 establishes a circuit extending from the positive terminal of a separate source of electrical energy through the segment 396 of master controller 136, segment 390 of controller 142, contact member 374, winding 370 of contactor 362, and limit switch 356 to the negative terminal of the separate source of supply whereby the winding 370 is so energized as to effect a movement of the contact member 366 upwardly to a circuit closing position. By establishing the circuit which extends from the positive terminal of the separate

source of supply through the contact member 366, armature member 60 of the motor 54 and contact member 368 to the negative terminal of the source of supply, the motor 54 is operated to raise the electrode 20.

If the flow of current in the conductor 26 is large as, for example, where a short circuit is encountered, the current transformer 346 is so energized as to effect an operation of the protective device 348 to actuate its contact member 348 to a circuit closing position to effect the energization of the winding 328 of the trip device 330. When this occurs the circuit breaker 36 is tripped and the contact member 326 of the breaker 36 establishes a circuit from the ungrounded end of winding 264 of relay 258 to the conductor 24. If the short circuit still exists, the winding 264 is shunted to effect the deenergization thereof, whereby its contact member 270 moves to an open circuit position to deenergize the winding 272 of the switching device 134 and cause the contact members 274 and 400 to move to an open circuit position and the contact members 402 to move to a circuit closing position. The movement of the contact members 402 establishes circuits to effect the operation of the electrode motors to cause them to raise the electrodes. The circuits are similar for each of the regulators and may be understood by reference to the circuit 30 extending from the positive terminal of a separate source of supply, through contact member 402 of the switching device 134, winding 370 of contactor 362, limit switch 356 to the negative terminal of the separate source of supply. The establishment of these circuits effects the operation of the electrode motors to raise the respective electrodes.

As long as the short circuit condition on any one of the electrodes is maintained, the contact member 326 of breaker 36 functions to effect the shunting of the winding 264 of relay 258. However, as soon as the short circuit condition is cleared, the winding 264 of relay 258 again becomes energized whereby the operation of relay 258 effects the energization of the switching device 134 to again establish the circuits referred to hereinbefore.

With the switching device 134 and the breaker 36 in their circuit closing positions, if it is desired to independently effect the positioning of any one of the electrodes 16, 18 and 20, the individual controllers 138, 140 and 142, respectively, can be moved to the "raise" or "lower" position depending upon the change in position of the electrodes desired. If, for example, it is desired to lower the electrode 20 independently of the electrodes 16 and 18, only the controller 142 is moved to the "lower" position where the segment 388 closes a circuit extending from the positive terminal of the source of supply through contact member 400 of switching device 134, segment 388 of controller 142, winding 372 of contactor 364 and the limit switch 358 to the negative terminal of the separate source of supply. The closing of this circuit effects the energization of the contactor 364 whereby its contact member 368 moves upwardly to establish the circuit to cause the motor 54 to operate in the direction to effect the lowering of the electrode 20.

If it is desired to raise the electrode 20 independently of the electrodes 16 and 18, then the controller 142 is moved to the "raise" position to establish the circuit extending from the positive terminal of the separate source of supply through the segment 392, winding 370 of contactor 362

and the limit switch 356 to the negative terminal of the separate source of supply. The contactor 362 is thus energized to actuate its contact member 366 upwardly to establish a circuit to cause a flow of current through the armature 60 in such a direction as to effect the operation of the motor 54 in a direction to raise the electrode 20.

The limit switches 356 and 358 are effective for opening the circuits to the windings 370 and 372, respectively, of the contactors 362 and 364, respectively, to prevent operation of the motor 54 to move the electrode 20 in either the raise or lower direction beyond predetermined limits. Similar operation of the electrode motors may be had for controlling the position of the electrodes 16 and 18.

In both of the embodiments described hereinbefore, it is, of course, apparent that the circuit breakers 36 may be moved to a circuit opening position at the will of the operator as the movement of the contact member 318 carried by the circuit breaker 36 to the circuit closing position effects the energization of the winding of relay 260 whereby the contact member 278 is moved to a circuit opening position to effect the deenergization of the relay 262 and consequently the deenergization of the winding 284 of the circuit breaker. The operation of the relay 260 is substantially instantaneous with the closing of the contact member 318 so that the energizing winding 284 is deenergized even though the switch 276 is held in a circuit closing position. Under such conditions, the manual operation of the switch 332 to a circuit closing position closes the circuit from the separate source of supply through the winding 328 of the trip device 330 to release the circuit breaker 36 at any time that the operator desires to interrupt the circuit which supplies the power to the power transformer 38.

By employing the circuits and apparatus of this invention, it is impossible to reclose the circuit breaker against a short circuit fault, adequate provision having been made for effecting the clearing of the fault before a circuit breaker can be closed. The circuits and apparatus of this invention consequently prevent flashover in the breaker, together with possible damage to the power transformer and regulating equipment. The invention utilizes standard apparatus and can be readily duplicated in the numerous types of regulating systems now available.

We claim as our invention:

1. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be

energized when the circuit breaker is in a circuit closing position to effect the deenergization of the winding of the circuit breaker, means operable under short circuit conditions of the electrode 5 when the circuit breaker is in the circuit opening position to effect the deenergization of the relay means, and means responsive to the deenergization of the relay means to connect the means responsive to the arc current to be energized to effect the raising of the electrode.

2. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under short circuit conditions of the electrode to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of 20 the winding of the circuit breaker, means carried by the circuit breaker operable under short circuit conditions of the electrode to effect the deenergization of the relay means when the circuit breaker is in the circuit opening position, and means responsive to the deenergization of the relay means to connect the means responsive to the arc current to be energized to effect the raising of the electrode.

3. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be 40 energized, another relay means disposed to be energized when the circuit breaker is in a circuit closing position to effect the deenergization of the winding of the circuit breaker, means operable under short circuit conditions of the electrode when the circuit breaker is in the circuit opening position to effect the deenergization of the relay means, and means carried by the relay means disposed when the relay means is deenergized to connect the means responsive to the

arc current to be independently energized to effect the raising of the electrode.

4. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under short circuit conditions of the electrode to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the de-energization of the winding of the circuit breaker, means carried by the circuit breaker operable under short circuit conditions of the electrode to effect the deenergization of the relay means when the circuit breaker is in the circuit opening position, and means carried by the relay means disposed when the relay means is deenergized to connect the means responsive to the arc current to be independently energized to effect the raising of the electrode.

5. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in a circuit closing position, means operable under short circuit conditions of the electrode to release the holding means whereby the circuit breaker moves to a circuit opening position, means manually operable for also releasing the holding means, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the de-energization of the winding of the circuit breaker, means actuated by movement of the circuit breaker to the circuit opening position to be operable under short circuit conditions only of the electrode to effect the deenergization of the relay means, and means responsive to the arc current to be energized to effect the raising of the electrode.

6. In a system for controlling the feeding of an electrode and the production of an electric arc supplied from a source of power supply, in combination, a power transformer connected to the electrode, a circuit breaker disposed to con-

nnect the power transformer to the source of power, a winding for the circuit breaker disposed to be energized to actuate the circuit breaker to a circuit closing position, means for normally holding the circuit breaker in circuit closing position, means operable under short circuit conditions of the electrode to release the holding means whereby the circuit breaker moves to a circuit opening position, means manually operable for also releasing the holding means, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means actuated by movement of the circuit breaker to the circuit opening position to be operable under short circuit conditions only of the electrode to effect the deenergization of the relay means, and means carried by the relay means disposed when the relay means is deenergized to connect the means responsive to the arc current to be independently energized to effect the raising of the electrode.

7. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the de-energization of the winding of the circuit breaker, the holding means maintaining the circuit breaker in circuit closing position until the releasing means is operated, means operable under short circuit conditions only of the electrode when the circuit breaker is in a circuit opening position to effect the deenergization of the relay means, and means carried by the relay means disposed when the relay means is deenergized to connect the means responsive to the arc current to be independently energized to effect the raising of the electrode.

8. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position,

means operable under predetermined conditions to release the holding means whereby the circuit breaker moves to a circuit opening position, a motor disposed for raising and lowering the electrode, means connected to be responsive to the arc potential to effect the operation of the motor to lower the electrode, means connected to be responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means operable under short circuit conditions only of the electrode when the circuit breaker is in the circuit opening position to effect the deenergization of the relay means, means operable when the circuit breaker is in the circuit opening position to disconnect the means responsive to the arc potential whereby the motor will not operate to lower the electrode, and means responsive to the deenergization of the relay means to connect the means responsive to the arc current to be energized to effect the raising of the electrode.

9. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means connected to be responsive to the arc potential to effect the operation of the motor to lower the electrode, means connected to be responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means carried by the circuit breaker operable under short circuit conditions only of the electrode to effect the deenergization of the relay means when the circuit breaker is in the circuit opening position, means operable when the circuit breaker is in the circuit opening position to disconnect the means responsive to the arc potential whereby the motor will not operate to lower the electrode, and means responsive to the deenergization of the relay means to connect the means responsive to the arc current to be energized to effect the raising of the electrode.

10. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position.

means operable under predetermined conditions to release the holding means whereby the circuit breaker moves to a circuit opening position, a motor disposed for raising and lowering the electrode, means connected to be responsive to the arc potential to effect the operation of the motor to lower the electrode, means connected to be responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means operable under short circuit conditions only of the electrode when the circuit breaker is in the circuit opening position to effect the deenergization of the relay means, means operable when the circuit breaker is in the circuit opening position to disconnect the means responsive to the arc potential whereby the motor will not operate to lower the electrode, and means carried by the relay means disposed when the relay means is deenergized to connect the means responsive to the arc current to be independently energized to effect the raising of the electrode.

11. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means responsive to the arc potential to effect the operation of the motor to lower the electrode, means responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means operable under short circuit conditions only of the electrode when the circuit breaker is in the circuit opening position to effect the deenergization of the relay means, means responsive to the deenergization of the relay means to connect the means responsive to the arc current to be independently energized to effect the raising of the electrode, and means disposed to be manually operated to selectively connect the means responsive to the arc potential and the means responsive to the arc current to be independently energized when the relay means is energized to selectively lower or raise the electrode.

12. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be energized to actuate the circuit breaker to a circuit closing position, means for normally holding the circuit breaker in circuit closing position,

means operable under predetermined conditions to release the holding means whereby the circuit breaker moves to a circuit opening position, a motor disposed for raising and lowering the electrode, means connected to be responsive to the arc potential to effect the operation of the motor to lower the electrode, means connected to be responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means operable under short circuit conditions only of the electrode when the circuit breaker is in the circuit opening position to effect the deenergization of the relay means, means operable when the circuit breaker is in the circuit opening position to disconnect the means responsive to the arc potential whereby the motor will not operate in response to the arc potential, means responsive to the deenergization of the relay means to connect the means responsive to the arc current to be independently energized to effect the raising of the electrode, and means disposed to be manually operated to selectively connect the means responsive to the arc potential and the means responsive to the arc current to be independently energized when the relay means is energized to selectively lower or raise the electrode.

13. In a system for controlling the feeding of an electrode and the production of an electric arc supplied from a source of power supply, in combination, a power transformer connected to the electrode, a circuit breaker disposed to connect the power transformer to the source of power, a winding for the circuit breaker disposed to be

energized to actuate the circuit breaker to a circuit closing position, means for normally holding the circuit breaker in circuit closing position, means operable under predetermined conditions to release the holding means whereby the circuit breaker moves to a circuit opening position, a motor disposed for raising and lowering the electrode, means connected to be responsive to the arc potential to effect the operation of the motor to lower the electrode, means connected to be responsive to the arc current to effect the operation of the motor to raise the electrode, relay means disposed to be energized under predetermined conditions to connect the winding of the circuit breaker to be energized, another relay means disposed to be energized when the circuit breaker is in a circuit closing position to effect the deenergization of the winding of the circuit breaker, means actuated by movement of the circuit breaker to the circuit opening position to be operable under short circuit conditions only of the electrode to effect the deenergization of the relay means, means operable when the circuit breaker is in the circuit opening position to disconnect the means responsive to the arc potential whereby the motor will not operate in response to the arc potential, means carried by the relay means disposed when the relay means is deenergized to connect the means responsive to the arc current to be independently energized to effect the raising of the electrode, and means disposed to be manually operated to selectively connect the means responsive to the arc potential and the means responsive to the arc current to be independently energized when the relay means is energized to selectively lower or raise the electrode.
